Primary Examiner — Leanne Was-Englehart*(74) Attorney, Agent, or Firm* — Perkins Coie LLP(57) **CLAIM**

The ornamental design for a hinge portion of a microphone accessory, as shown and described.

DESCRIPTION

FIG. 1 is a perspective view of a hinge portion of a microphone accessory showing my design, as viewed from the top and front.

FIG. 2 is a front elevational view thereof.

FIG. 3 is a back elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The uneven broken lines depict the limits of the claimed design. The portions between the uneven broken lines form no part of the claimed design.

1 Claim, 2 Drawing Sheets(56)
